INVENTOR
NATHAN RITTER
BY *Murphy*
ATTORNEYS

UNITED STATES PATENT OFFICE.

NATHAN RITTER, OF BROOKLYN, NEW YORK.

CLIP.

Application filed April 11, 1923. Serial No. 631,413.

To all whom it may concern:

Be it known that I, NATHAN RITTER, a citizen of the United States, and a resident of the city of New York, borough of Brooklyn, in the county of Kings and State of New York, have invented a new and Improved Clip, of which the following is a full, clear, and exact description.

This invention has relation to an improvement in clips and contemplates a clip for associating with a sheet, card or other article, certain indicia carried by the clip.

One of the principal objects of the present invention is to provide a clip which in addition to performing the usual function of associating sheets or other articles with one another, is so constructed as to allow for its association with said articles or objects certain indicia or indicia bearing means, whereby a maximum number of displays on said indicia may be obtained.

In the general forms of clips as now constructed, the same define only one pair of clamping jaws or portions for engagement with the article or articles with which it is to be associated, thus limiting the application of the clip to said article or articles by sliding the same longitudinally thereover in one direction.

It is therefore a further object of the present invention to so improve the construction of the ordinary forms of paper clips to define a pair of clamping portions each having an entrance mouth disposed toward its opposite ends whereby the clip may be engaged by sliding the same longitudinally onto the article or articles with which it is associated from either end of the clip.

As a still further object the invention aims to produce a clip having covering means associated therewith which in addition to rendering the same more facile in its use, may also serve as a protection for indicia bearing means enclosed by said covering.

The invention furthermore aims to provide a clip of the character described which is extremely simple in its construction, inexpensive to manufacture and produce, and which is highly efficient in its purpose.

With the above recited and other objects in view, the invention resides in the novel construction set forth in the following specification, particularly pointed out in the appended claims and illustrated in the accompanying drawing, it being understood that

the right is reserved to embodiments other than those actually illustrated herein to the full extent indicated by the general meaning of the terms in which the claims are expressed.

In the drawing,

Figure 1 is a side view of a clip constructed in accordance with the invention and illustrating the same applied to a card, sheet or other article.

Fig. 2 is a similar view of the opposite side of the clip.

Fig. 3 is a sectional view taken approximately on the line 3—3 of Fig. 2.

Fig. 4 is a perspective view of the clip illustrated in Figs. 1, 2 and 3 with the covering removed.

Figs. 5, 6, 7, 8 and 9 are modified forms of the invention.

Referring to the drawing by characters of reference, the clip constituting the preferred embodiment of the invention and illustrated in Figs. 1 to 4 inclusive is constructed of a single length of wire bent medially upon itself to provide a transverse end 10, parallel side legs 11, and aligned ends 12 which project inwardly toward each other from the free ends of the side legs 11. A pair of spaced parallel intermediate legs 13 extend toward the end 10 and are bent laterally as at 14 to intersect approximately the center of the length of the clip.

The free ends of the laterally extending portions 14 are bent reversely as at 15 toward the ends 12 and lie within and engage the inner periphery of the side legs 11, the terminals 16 thereof being bent around the side legs 11 to dispose the same in a plane with the clip. Under this arrangement the laterally bent portions 14 of the intermediate legs 13 and the return bent portions 15 define together with that portion of the side legs which lie between the extremities 16 and the end 10 a pair of clamping jaws or portions for engagement over a card, sheet or other thin flat article or articles, the entrance of which jaw is disposed toward the end 10. The terminals 16 constitute a stop against which the inner edge of the sheet, card or other article engages to limit the application of the clip thereon. The terminal 16 and return bent portions 15 define together with that portion of the side legs which lies between the laterally bent portions 14 and the ends 12 a pair of clamping

100
105
110

jaws having an entrance mouth disposed towards the ends 12 and in this instance the laterally bent portions 14 constitute a stop against which the edge of the card, sheet or other article engages to limit the application of the clip thereto. Under this arrangement it will be evident that a clip is provided which is insertable over and engageable with a card, sheet or other article by longitudinal sliding of the same thereover from either end of the clip while a stop is formed to limit the sliding of the clip onto said article whereby a portion of the clip will normally project beyond the outer edge thereof. It therefore follows that the clip with suitable indicia bearing means carried thereon may be associated with the article in a maximum number of ways for displaying the various indicia. To this end, a suitable covering consisting of a sheet or strip of material 17 is hooked under the laterally bent portions 14 at one end, extends longitudinally of the clip and around the ends 12 to lie at one side of the clip and is thence extended along the opposite side around the end 10 with the other terminal lying between the terminal hooked around the laterally extending portions 14 and the lead 18 of the strip which lies parallel with the opposite face of the clip. The sheet or strip 17 may thus have inscribed directly thereon suitable indicia 19, 20, 21 and 22, which indicia may be selectively displayed by the various positioning of the clip on the article, namely, by slipping the clip from either end onto the article and by reversing the sides of the clip to face the observer. In lieu of directly inscribing the indicia on the sheet or strip 17, individual indicia bearing elements or cards 23 may be positioned within the strip or sheet 17 which in this instance will be of transparent material such as celluloid.

In the modified form illustrated in Fig. 5 of the drawings, the clip which is constructed of a single length of wire is bent medially upon itself to provide an end 25, lower side legs 26 which are bent inwardly toward each other at the free ends as at 27, reversely bent as at 28 at a right-angle to extend toward the end 25, laterally bent outward as at 29 and thence bent upwardly to provide upper side legs 30 which are disposed parallel and in alignment with the lower legs 26. The upper free ends of the upper side legs 30 are bent inwardly toward each other as at 31 to provide an upper end corresponding to the end 25. This construction produces a clip having clamping portions at its opposite ends with an entrance mouth for each pair of clamping portions disposed toward the opposite ends of the clip and the inner stop which is formed respectively by the portions 27 and 29. The

modified form illustrated in Fig. 6, the clip which is constructed from a single length of wire is bent medially to provide a lower end 32, parallel side legs 33 having inwardly projecting aligned portions 34 which are bent reversely toward the end 32 to provide inner parallel legs 35 which are bent laterally as at 36 at their free ends and formed with terminals 37 lying within and contacting with the side legs 33 at substantially the medial portion of said side legs. The ends of the terminals 37 are preferably bent or offset as at 38.

In the modified form illustrated in Fig. 7 the clip is identical in construction to that disclosed in Fig. 6 with the exception that the terminals 37 of the laterally bent portions 36 are imposed directly on the side legs 33 while the ends of the terminals 38 are curved laterally and around the side legs 33.

In the modified form illustrated in Fig. 8 which closely simulates the clip illustrated in Figs. 6 and 7, the terminals 37 are disposed outside and lie against the outer sides of the side legs 33 with the ends 38 thereof directed or curved forwardly. In the modification illustrated in Fig. 9 the terminals 37 which lie within the side legs 33 as illustrated in Fig. 6 are bent around the side legs 33 as at 39 and are formed with an extremity 40 which lies along the outer side of the legs 33 and projects toward the end 32.

It is of course to be understood that the modified forms of the clip may be equipped with a cover as set forth in the preferred embodiment, if desired, or that said modified forms together with the preferred embodiment may be used without the covering, as desired.

I claim:

1. As a new article of manufacture, a clip constructed of a length of material bent upon itself to define a pair of clamping portions at opposite ends each having an entrance mouth disposed toward the opposite ends of said clip, a common stop at the inner ends of each pair of clamping portions, and a cover for said clip extending around the length thereof.

2. As a new article of manufacture, a clip constructed of a length of material bent upon itself to define a pair of clamping portions at opposite ends each having an entrance mouth disposed toward the opposite ends of said clip, and indicia bearing means carried by said clip disposed on opposite sides and at opposite ends of the clip.

3. A clip constructed of a single length of wire bent medially upon itself to provide an end, parallel side legs, inwardly bent aligned portions at the free end of the side legs, longitudinally bent intermediate legs

extending from the inwardly bent portions toward the end, laterally bent portions at the free ends of the intermediate legs, reversely bent extremities at the free ends of the laterally bent portions extending toward the inwardly bent portions, and laterally curved transversely projecting terminals on said extremities, whereby to define a pair of clamping portions at the opposite ends of the clip each having an entrance mouth disposed toward the opposite ends thereof.

10 NATHAN RITTER.
